Primary Examiner — John Windmuller*Assistant Examiner* — Abraham Bahta(74) *Attorney, Agent, or Firm* — Whyte Hirschboeck Dudek S.C.(57) **CLAIM**

An ornamental design for a produce handbag, as shown and described.

DESCRIPTION

FIG. 1 is a front perspective view of a produce handbag showing our new design;

FIG. 2 is a front elevation view thereof;

FIG. 3 is a top plan view thereof;

FIG. 4 is a rear elevation view thereof;

FIG. 5 is a bottom plan view thereof;

FIG. 6 is a left elevation view thereof; and,

FIG. 7 is a right elevation view thereof.

The broken lines in the drawings represent unclaimed environmental matter.

The oblique shade lines in the Figures represent a transparent or a translucent surface.

1 Claim, 4 Drawing Sheets(56)
